SHOE DISPLAY FORM

Herman Brickman, New York, N. Y.

Application April 7, 1950, Serial No. 154,590

3 Claims. (Cl. 12—128.5)

1

This invention relates to novel shoe display forms. In particular, it is directed to a novel device of this class having means for readily elevating the portion thereof that extends rearwardly from the ball, and also having means for adjusting the widths thereof.

Many proposals have been advanced with respect to improving the structure of shoe forms, especially those made of a plastic shell, for the better displaying of shoes. But such forms are designed for use only with a specific last, or at best, a slight modification of the last. In particular, the attempts heretofore made to provide a single shoe display form which is adapted for use in displaying shoes built on a variety of lasts that vary greatly in heel heights, and also the widths, if desired, have failed to accomplish such purpose.

I have conceived of a means for providing the art with a multi-purpose shoe display form which may be made by a relatively simple process of molding and assembly of members which is adapted for insertion in shoes of various heights and widths. I have also conceived of a means of providing a basic shoe display form, so that it is useful for displaying shoes of various widths.

In its fundamental aspects this invention is directed to a shoe form made of a combination of two plastic shells (each molded in one piece) which are pivoted at the ball. The rearward shell may also be provided with integrally molded means to receive a brace that provides a plurality of widths so that the width of the form may be varied as desired.

The provision of the integrally formed means for engaging the appropriate elements of the brace presents a striking advance in this art. It eliminates the various complicated structures heretofore proposed to accomplish the ends that this invention provides.

Accordingly it is among the principal objects of this invention to provide a shoe display form adapted for use in exhibiting shoes built on a variety of lasts, thus enabling one to use a single unit for displaying shoes of various heel heights.

A further object is to provide a shoe display form adapted for use in exhibiting shoes built on a variety of lasts thereby to enable one to use a single unit for displaying of varying heel heights as well as varying widths.

Another object of this invention is to provide a shoe display form made from a shell having the shape of a foot provided on the inner flexible sides of said shell in the region rearwardly of the ball with integrally formed means for engaging

the ends of braces of various widths whereby the width of the shoe display form may be adjusted for the display of shoes of varying widths.

A further object of the invention is the provision of a novel brace used to vary the widths of the above described shoe forms, the variation in width being accomplished by the provision of a brace having a plurality of bracing arms or members of various lengths terminating in elements adapted to be received by appropriate means in the shoe display form that engages the same.

A further object of this invention is the provision of a novel brace used to vary the widths of a shoe display form, of the class above described, wherein the variation is accomplished by providing the brace with a plurality of bracing arms of various lengths terminating in elements adapted to be received by appropriate means in the shoe display form that engages the same, the bracing arms terminating on one side in a common element adapted to be received by the means for engaging the same in the shoe display form.

The foregoing objects, as well as other objects and advantages, will become more apparent from the following detailed description of the invention taken in connection with the accompanying drawings wherein:

Fig. 1 is a perspective view, as seen from the bottom, of a shoe display form for use with flat shoes made in accordance with this invention and showing the brace in position.

Fig. 2 is a side elevation of a shoe display form used for displaying shoes of varying heel heights, the embodiment illustrated being shown as used for displaying a Cuban-wedged heel variety.

Fig. 3 is a view of the forepart of the embodiment illustrated in Fig. 2 as seen from the bottom thereof.

Fig. 4 is a side view of the shoe display form illustrated in Fig. 2 as the same is positioned for use in displaying a high heeled shoe.

Fig. 5a is a side elevation of the brace shown in Figs. 1 and 3.

Fig. 5b is a top plan view of the said brace illustrated in Fig. 5a.

In the drawing the numeral 10 designates a shell molded in the form of a foot. The sides of said shell are flexible. At about midway the length thereof, i. e., in the region rearwardly of the ball, and at the bottom, the shell is provided with inwardly extending collars or ears 12 and 14 each having a vertical slot as at 16 and 18, and a bore as at 20 and 22, the bores communicating 55 with the aforesaid slots. The ears may be mold-

ed integrally with the form 10. The form 10 is given rigidity by the brace 26, which is mounted within the inside of the form. The brace 26 which may be molded from a plastic is provided with a plurality of fanned out bracing arms 30, 32, and 34 formed integrally with the same. The bracing arms are of varying lengths. The bracing arms have a common single extremity 38 in the form of a substantially pinlike element, while each oppositely disposed extremity of the several arms is made in similar form as at 40, 42 and 44. An oppositely disposed pair of these pinlike elements are inserted into the vertically extending bores 20 and 22 hereinabove described so that the shell 10 is braced and made rigid.

As shown in Fig. 2 the shoe display form 50 comprises the toe section 52, and a rear section 54, each made of a molded piece. Section 52 encompasses substantially the toe portion of the form 50 and extends rearwardly to about the point of greatest width of the shoe. The rear section 54 terminates forwardly in a depressed or indented end 55 extending transversely thereof. Section 52 and section 54 are pivotally joined to each other near the base as by rivets 58 and 60, or any other appropriate means. Section 54 is provided with brace engaging means as at 64 and 66, said brace-engaging means being similar in structure to the corresponding members 12 and 14 of Fig. 1.

It will be observed that it is possible to use this form for displaying shoes of various heel heights as well as various widths. By elevating or lowering the rear section 54 with respect to the front section 52 it is possible to adjust the form to fit into shoes of various heel heights.

The widths of the display form may be adjusted to a desired dimension by use of the brace having a plurality of bracing arms of desired length as hereinabove described.

It will also be noted that this shoe display form may be used as a shoe tree as well as for the display of shoes on the counter or in a store window.

It will be understood that the foregoing description of this invention and the embodiments illustrated are merely illustrative of the principle thereof; and, accordingly that the appended claims are to be construed as defining the invention within the full spirit and scope thereof.

I claim:

1. A shoe display form comprising a plastic

shell in the form of a foot and having flexible sides, the inner faces of said sides being provided, approximately midway the length thereof, with means for engaging a removable brace, the form having a toe section that is pivotally connected to the body thereof whereby the structure may be used for the display of shoes of varying heel heights.

2. A shoe display form comprising a plastic shell in the form of a foot and having flexible sides, the inner faces of said sides being provided, approximately midway the length thereof, with means for engaging a removable brace, and a width adjusting brace comprising a plurality of arms of varying length, the said arms terminating in an element adapted to be inserted in the aforesaid means for engaging said brace, the arms of varying length having at least one terminal element common to all.

3. A shoe display form comprising a plastic shell in the form of a foot and having flexible sides, the inner faces of said sides being provided, approximately midway the length thereof, with means for engaging a removable brace, the form having a toe section that is pivotally connected to the body thereof whereby the structure may be used for the display of shoes of varying heel heights, said removable brace being adapted to adjust the width of the shoe form and comprising a plurality of arms of varying length, the said arms terminating in an element adapted to be inserted in the aforesaid means for engaging said brace, the arms of varying length having at least one terminal element common to all.

HERMAN BRICKMAN.
